UNITED STATES PATENT OFFICE.

LOUIS JOSEPH JEAN BAPTISTE CHÈNEAU, OF PARIS, FRANCE.

AERIAL RAILWAY.

Application filed February 7, 1922. Serial No. 534,726.

To all whom it may concern:

Be it known that I, LOUIS JOSEPH JEAN BAPTISTE CHÈNEAU, engineer, a citizen of the French Republic, residing at Paris, France, have invented certain new and useful Improvements in Aerial Railways, of which the following is a specification.

This invention relates to aerial railways or cableways, upon which tractors or other moving devices are adapted to run.

It has for its object so to mount and arrange the said aerial lines that they are more efficient than has hitherto been the case.

The invention consists essentially in so constructing railways of the class in question that the line or cable has uniform tension throughout, whatever may be the length of the line and the means employed for tensioning the extremities. In other words, no means are provided between the extremities for varying the tension which interrupt the continuity of the cable as regards the device running thereon. This result is obtained by maintaining the tension of the cables by displacing a certain number of the intermediate points of attachment of the said cable, in a direction substantially transversal to the extension of the cable. The lateral displacements are conveniently realized in such manner that their intervention serves to absorb the slack of the cable which takes place in the summer, or as a consequence of its extension. The lateral displacement can take place either horizontally or vertically or in an oblique direction, the displacement being effected in a straight line section of the cable so that said cable becomes slightly zigzagged after the correction of the slackening. The zigzagged condition in straight sections is greater in the summer and less zigzagged or almost straight in the winter. In curved parts of the track the supporting points are moved slightly outward in tightening the cable. In moderate weather the zigzagged condition of the track will be in proportion to the temperature.

The invention includes, in addition to the principal feature just mentioned, a certain number of other arrangements, which are

preferably employed at the same time as the principal feature or arrangement, but which can be employed independently thereof and which will be more fully described hereafter. In particular, a construction or arrangement may be provided in which each of the supports for the cable consists of a post or upright, provided either with an inclined stay or with a guy rope, and an arrangement in which the displacement of the point of attachment of the cable is obtained by means of a device for regulating in an appropriate manner one of the elements of the triangle formed with the ground by the post or upright and the inclined stay or guy rope.

The invention further includes certain constructional embodiments of its principles and more particularly and that by way of new industrial products, aerial railways having such principles adapted thereto, as well as special parts suitable for the construction of such railways.

In order that the said invention may be clearly understood, I will now proceed to describe the same with reference to the accompanying drawings, it being clearly understood that the description and drawings are given merely by way of example.

Fig. 1 of the drawing shows, partly in elevation and partly in section, a portion of an upright provided with means for enabling the cable which it supports to be displaced, the said means being constructed according to the invention.

Fig. 1^a is a slightly different form of the device as shown in Figure 1.

Fig. 2 shows in diagrammatic elevation, one of the uprights in the normal position and in one of the positions in which the cable has been displaced by operating the said means.

Figs. 3 and 4 are part diagrammatic plans of an aerial railway provided with supports of the foregoing description and provided with means for displacing the cable.

Fig. 5 shows in elevation with parts broken away and parts dotted a jointed bracket or support to be carried by certain uprights of the aerial railway.

Fig. 6 shows in plan one of the parts of the said bracket.

Figs. 7 and 8 show respectively in elevation and in diagrammatic plan a portion of an aerial railway provided with brackets or supports of the last mentioned description, the line carrying a tractor towing a boat.

The drawings illustrate in general the preferred method of carrying out the invention as applied to the suspension of the cable of an aerial railway upon which a suspended tractor is adapted to run, and the construction is substantially as follows:—

a are uprights or posts, any appropriate number of which is provided, in the ordinary manner to suit requirements. Each of these is provided with a bracket to support the aerial line, and each of the brackets carries a gripping device b adapted to clamp the portion of the cable c to be supported by the bracket.

Some of the uprights are so constructed and arranged that the brackets which they carry can be pushed forward or drawn back for a certain distance substantially at right angles to the direction of the line to be carried.

This result may be obtained, with advantage, by providing each of the uprights with an inclined stay d, the upper end of which is connected to the upright in the neighbourhood of the bracket, means being further provided for enabling the point of connection between the inclined stay and the upright to be displaced.

These means are constituted preferably by providing two bearing lugs a' which carry a vertical spindle e, and which are attached to the upright. The spindle e is provided between the lugs with a screw thread upon which screws a nut f, which nut is pivotally mounted in a piece f' attached to the upper extremity of the inclined stay where it comes up to the post. Any suitable means are provided for rotating the screw threaded spindle e in the bearing lugs.

In this way the apex of the triangle A,B,C. shown at Fig. 2 can be displaced. In this triangle the side A.B represents the upright and the side B,C represents the inclined stay. The displacement is effected by varying the length of the side A.B, it being of course assumed that the relative movements of the upright and the inclined stay are rendered possible by the flexibility of the parts of the system and the slight displacement which can be given to the two elements in question where attached to the ground.

The same effect may be obtained by making the point B a fixed point with respect to the upright and by varying the length of the side B,C, for instance by means of a tensioning device interposed in any position in the said side. This application is par-

ticularly suitable in the case where a guy rope takes the place of the inclined stay and tensioning means are provided for the rope.

These arrangements are particularly suitable where the railway comprises portions which are curved, and where the uprights are already provided as a general rule with inclined stays, which it is only necessary to adapt so as to obtain the desired results.

This is indicated by way of example at Fig. 4 where the brackets are displaced from a to a'. In cases where the uprights are provided with inclined stays of the kind in question and arranged along a considerable straight length of railway, the regulation of the tension would be obtained by displacing the bracket upon the uprights either to one side or the other of the line of direction, namely from a to a', as shown at Fig. 3.

With the foregoing construction and arrangement the unavoidable variation in length of the cable can be corrected between its extremities which are supposed to be suitably anchored. Hitherto, the only means of correction adopted has been to divide the line into sections, in each of which the cable is under the tension of a counterbalanced weight or spring. This is an expensive arrangement and is also inconvenient if the line is of some considerable length, the interruption of the line leading to complication in relation to the passage of the tractor from one section to the other.

I prefer, in addition to the foregoing arrangements which give every satisfaction in themselves, to provide some or all of the following constructions.

I may construct some of the brackets as shown at Figs. 5, 7 and 8. In this case each bracket comprises three portions g, g' and g'', pivotally connected together by means of vertical pins h and i.

The portion g'' of the bracket which supports the gripping device b may be so constructed that the said device can oscillate about a pivot j perpendicular to the pivotal axes h and i, the pivot j being located in the said part beyond the pivotal axis i.

Each of the grips b may be constructed as shown at Fig. 6, from a plurality of gripping members coming into juxtaposition at their extremities. Each of these members may comprise claws pressed towards one another by means of a screw k, shown only on Fig. 5, the devices being preferably formed in two portions and so that they can engage one another in a manner shown clearly at Fig. 5.

In the foregoing manner, I obtain an aerial railway which is admirably adapted for the movements thereon of a tractor l suspended therefrom, as shown at Fig. 7. In addition to the advantages already enumerated, which are obtained by the regulation of the variations of length of the cable, if

the jointed brackets are fitted, there is the additional advantage that when the tractor is between two consecutive brackets, the weight of the tractor, which causes the cable 5 to bend in the intervening space, makes the brackets bring the grips which they carry towards one another. At the same time each of the grips whilst being displaced parallel to itself tips so as appreciably to lengthen 10 the corresponding portion of the cable which sags. The result is that the pull exerted by the tractor upon the cable between two consecutive hinged brackets has less tendency to pull down the supporting post 15 for the brackets than if the cable were attached to fixed brackets. As the jointed brackets yield under the pull a certain amount of cable is given out from each of the brackets under consideration to the bending 20 or sagging portion of the cable, whilst at the same time the pull of the sagging portion of the cable is transmitted to the neighbouring length and so on to the anchored portions of the line or it may be 25 transmitted to intermediate fixed portions located at suitable distances and preferably constituted by brackets which are not hinged, such brackets being attached to reinforced supports.

30 As the gripping devices of the two consecutive jointed brackets incline to one another as has been explained, there is no danger of a localized bend of the cable in the neighbourhood of the said gripping devices.

35 In some cases the gripping members may be thinned away towards the extremities, and with this construction and owing to the fact that they are adapted to tip, the passage 40 of the running pulleys or wheels of the tractor is facilitated. At the moment that the wheels pass from one side to the other of the bracket, the gripping device tips over to an inclination contrary to that which it 45 occupied previously.

As will be readily understood and as has moreover been already stated, the invention is not limited in any way to those methods of carrying it into effect or to those constructional embodiments which have been described in detail.

On the contrary, it includes all modifications coming within a fair interpretation of my claims.

55 For instance the regulating means for controlling the positions of the brackets might comprise an elastic system interposed in any suitable position in the unit constituting the uprights or supports. For example 60 the elastic means might be interposed between the inclined stay and the corresponding upright, and it might be adapted automatically to rectify the tension of the cable irrespective of variations in length. It suffices in Fig. 1 to replace the action of the

turning of the threaded spindle by the construction shown in Fig. 1^a. The threaded spindle *e* of the Fig. 1 corresponds to the spindle *e'* of Fig. 1^a. This spindle is not threaded, but the nut becomes a simple eye *f'*, 70 and a spring *m* is inserted between one of the bearing lugs *a'* and the eye.

Owing to this construction an automatic zig-zagging of the cable can be obtained in a straight line section when every first of 75 two consecutive uprights is provided with a spring tending to push the eye upwards and every second of said two consecutive uprights is provided with a spring pressing the eye downwards. The track line thus becomes slightly zigzagged when the wire is slack and becomes automatically almost straight when the wire is very taut. In curves the springs of the uprights act all in the same direction, for example in pressing 80 the eyes upward.

What I claim and desire to secure by Letters Patent of the United States of America is:—

1. In an aerial railway, a cable fixedly anchored at its two ends and constituting a track, a plurality of uprights carrying said track, cable holding points movable on said supports, means adapted to permit displacement of the cable holding points for adjustment thereof at the will of the operator in such a manner that the track will assume in straight sections thereof a slightly zigzagged condition and in curved sections a slight general centrifugal displacement in tensioning the slackened wire, the zigzagged condition being eliminated when a slackening of the cable is desired.

2. In an aerial railway, a track, a plurality of supports for the track, each said support comprising an upright element furnished with means for carrying the track, an inclined element supporting the said upright element, means for varying the length of one of the said elements, and means causing the horizontal displacement of the top of said uprights whereby the stress of the track is regulated.

3. An aerial railway comprising a plurality of supports for the track, some of such supports being constituted by an upright element furnished with a bracket and carrying the track, and an inclined element pivotally connected thereto, with means for varying the length of each of the said elements, substantially as described.

4. In an aerial railway a support for the track, comprising an upright, a bracket, carried by the said upright, gripping means upon the said bracket for holding the cable, means in the neighbourhood of the bracket for holding a rotatable screw threaded rod, an inclined strut for the said upright, such strut being provided at the top with pivotal means for carrying a nut engaging the screw 125 130

threaded portion of the said rod, and means for rotating the said rod when required, for the purposes set forth.

5. In an aerial railway, a support for the track, comprising a bracket, consisting of three portions, an inner portion rigidly connected to an upright, an intermediate portion pivoted to the first mentioned portion

by a vertical pivot pin and an outer portion pivoted to the intermediate portion also by a vertical pivot pin with means carried by the outer portion for gripping the cable, for the purposes set forth. 10

In testimony whereof I have hereunto set my hand.

LOUIS JOSEPH JEAN BAPTISTE CHÊNEAU.
